(57) **CLAIM**

The ornamental design for a three-sided folding hanging mirror, as shown and described.

DESCRIPTION

FIG. 1 is a perspective view of a three-sided folding hanging mirror showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof; and,

FIG. 9 is in folding condition thereof.

The broken lines in the figures are for the purpose of illustrating portions of the three-sided folding hanging mirror, which form no part of the claimed design.
